Patented Oct. 17, 1922.

UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SELECTING SYSTEM.

Application filed January 24, 1919. Serial No. 272,955.

To all whom it may concern:

Be it known that I, WINFRED T. POWELL, a citizen of the United States, residing in Rochester, in the county of Monroe and 5 State of New York, have invented certain new and useful Improvements in Automatic Telephone Selecting Systems, of which the following is a full, clear, concise, and exact description.

10 My invention relates to telephone systems, and more particularly to such systems as are well-known in the art as automatic telephone systems, wherein any one of a number of subscribers to the system may without the 15 manual aid of an operator, operate the central station switching apparatus under the control of the subscriber substation apparatus to interconnect the calling subscriber's line with a desired one of the other 20 subscribers' lines.

An object of my invention is to provide an improved organism for such a system as will attain great efficiency of operation with the minimum of failures, this being accomplished with a relatively small amount 25 of apparatus operating in a most positive manner.

It is a further object of my invention to provide a novel means of controlling the 30 movements and release of the switch mechanism employed in interconnecting the lines; other objects of my invention and the invention itself will be made apparent from the description of the same which follows, and 35 in which description reference is made to the accompanying drawing showing a preferred embodiment of my invention.

Referring to the drawing, at A and B I show two telephone substations comprising 40 talking and signalling apparatus, as will be later more fully described herein, these substations being connected by telephone lines to main station apparatus individual to each of the lines; this main station line 45 apparatus being shown at L for the calling line station A, and at M for the called line station B.

It will be understood that either of these stations might be the calling or called station, but for convenience in this description, it will be assumed that the calling station A is seeking a connection with a called

station B; other telephone lines for other stations would of course be provided for such a system as herein described.

At CN, I show a telephone line interconnecting circuit consisting of a directively operated numerical switch mechanism, not shown in detail but which may be of any of the well-known forms of switch mechanism commonly used in the art to which this invention appertains, and it will be assumed in this description that the switch mechanism is of the type whose outgoing wipers, by which connection is made to a 65 desired called line, are moved first in a primary direction under the control of calling substation apparatus, and thereafter moved in a secondary direction under subsequent control by the calling substation 70 apparatus. Other equivalent forms of switching mechanism are contemplated.

In the operation of the system, as will be shown, when the calling substation A makes a call the circuit of the calling line is extended through traveling switch wipers of an individual switch associated with the calling line to co-operating circuits of the switch mechanism CN, and thereafter extended through the said switch mechanism 80 CN when the said switch mechanism is operated under the calling substation control, through the terminals of a called line which comprise contacts associated with the called line adapted to be engaged by the traveling 85 switch wipers of the switch mechanism CN.

The substation A comprises a transmitter *t*, adapted to be energized by current flowing over the line from the central station, a receiver *r*, an induction coil *i*, together with the usual telephone bell and serially connected condenser illustrated by the usual symbols, switch hook contacts 8 adapted to control the connection of the substation apparatus with the line conductors 1 and 2 of the calling line; also included at the substation A are contacts 7, 45, 46 and 47 of a subscriber's selective switch controlling mechanism, comprising the usual form of "2 wire" dial.

The controlling mechanism for these contacts is so organized, that when the subscriber gives the dial the preliminary forward movement, contact 45 opens and con-

tacts 46 and 47 close. The circuit connection thereupon causes the contacts 46 to short circuit the transmitter *t*, and the contacts 47 to short circuit a winding of the 5 induction coil *i*. As the dial returns to normal in the usual way, the substation impulse springs 7 are opened a definite predetermined number of times corresponding to the digit of the desired line number at the 10 time being dialed, the operations of the springs 7 being but momentary and occurring in rapid succession.

Immediately after the last interruption of the circuit by the contact 7, as described, 15 and prior to the subsequent closure of these contacts, contacts 46 and 47 are opened, and contact 45 is closed to place the substation relay C of the substation apparatus in circuit with the line. This relay C contains 20 normal contact 6 in circuit with the contact 7, so that when the relay C is operatively connected in circuit that the line current over the line will operate the relay C, and its contact 6 in the circuit of the contact 25 7 being opened, the subsequent closure of the contact 7 will be impotent. The relay C is of relatively high resistance for a purpose to be made clear in the description of the connector switch relays T and R.

30 At the main station for the line containing the substation A and which leads by circuit conductors 1 and 2 to the main station, there is provided a line switch having wipers 17, 24, 4, 14 and 10 which normally rest upon a 35 set of "home" passive contacts, a plurality of which are preferably provided, although a single set will suffice. Such a plurality of "home" passive contact sets will preferably be interposed between alternate sets of 40 "trunk point" passive contacts to each set of which circuit conductors leading to the controlling circuits of a connector switch mechanism CN will be connected. Such a home point contact set is, for instance, at 16, 23, 45 3, 13 and 11. A passive set of trunk point contacts is shown at 222, 32, 35, 104 and 36, these being connected by circuit conductors to the connector switch mechanism CN. Other sets of trunk point contacts will be 50 preferably provided for the switch, such another set being shown, for instance, as the set containing the contact 31.

The line switch wipers are controlled in their movements by stepping magnet ST, 55 designated 29, having a reciprocating armature and contacts 28. The line relay LR and the cut-off relay CO, for the line, co-operate in the control of this stepping magnet. The line switch mechanism including the said 60 stepping magnet and relays, is adapted to operate to connect the calling line through the line switch wipers and trunk point switch contacts of such a switch mechanism as CN as may at the time be idle, to the circuits of such a switch mechanism, connec-

tion being had through the circuit conductors as 33, 34, 38 and 37 for the switch mechanism CN.

Associated with the switch mechanism CN, is a primary stepping magnet PM 70 adapted to step the connector switch wipers 57, 58 and 59 in a primary direction, and a secondary stepping magnet SM to thereafter step the said wipers in a secondary direction, whereby connection is made with the 75 called line terminals, such as the terminals 72, 87 and 80 of the desired called line. Controlling the operation of the primary and secondary stepping magnet, is an escape magnet ESC which operates upon each de-energization to advance the side switch wipers 52, 68, 69, 65 and 70 from one operative position to another in the well known manner, also a step by step switch comprising wipers 43, 41 and 44 and a stepping magnet MO therefor, also relays T and R which exercises primarily a control over the said step by step switch, the escape magnet and the primary and secondary stepping magnets. 80 85 90

Associated also with the switch mechanism is a busy test relay BY, a ringing trip relay TR, a release magnet REL, a release relay RL controlling the said release magnet, and other apparatus and circuit organizations which will be more fully described in the narrative of the operation of the system which will later follow. 95

For a plurality of switch mechanisms, as CN, there is provided a timing circuit controlling means, consisting in the embodiment illustrated, of a pair of rotary commutators 121 and 122 mounted on a shaft 113, which is continuously rotated to cause the successive operation of the contacts 92 100 and 93 by the said commutators, the commutators being so organized as to provide a definite time interval between successive operations of the two contact sets 92 and 93 respectively. 105 110

A ringing source of current and auxiliary apparatus, common to a plurality of switch mechanisms, is shown as a ringing generator GN, an interrupter INT, and a resistance lamp LP. A source of busy tone current 115 BZ, common to a plurality of switch mechanisms, is also indicated in the drawing. Whereas a plurality of sources of operating current is shown in the drawing for the purpose of simplifying the same, it will be understood if desired only a single source of such a continuous source of current may be used, the various circuit conductors leading to the two poles of the various illustrated sources then being multiply connected to the 120 two poles of a single source. Thus having therefore set forth the various operative parts of the system of my invention, a narrative of a sample operation of the same will 125 now be had to better describe the functions 130

of the various parts and of the results achieved by the co-operative action of the various elements.

In this narrative of operation it will be assumed that the substation A is the calling substation and the substation B is the called one of a plurality of other substations, and the description will be made with the assumption that the called line is idle and a connection therefore had with the called line, and also description of the system as operated when the called line is busy will be had.

The subscriber at substation A, upon 15 moving his receiver *r*, closes a circuit to operate the line relay LR of line switch L as follows: ground G, terminal 3 and wiper 4 of line switch L, contact 5 of cut off relay CO, line conductor 2, contact 6 of relay C at substation A, impulse contact 7, transmitter *t*, switch hook contact 8, induction coil *i*, line conductor 1, contact 9 of relay CO, line switch wiper 10 and terminal 11 thereof, winding of line 20 relay LR to the source of current. The line relay LR operates and closes the following circuit to operate the line switch cut off relay CO:—ground GA, contact 12 of relay LR, terminal 13 and line switch wiper 14, winding 15 of relay CO to the source of current. This ground GA also is extended, from wiper 14 by way of terminal 16 and line switch wiper 17, to connector terminal 18, which path causes the calling line to test 25 busy to incoming calls the instant the line relay LR operates. The cut off relay CO operates over the previously traced circuit and breaks the original circuit of relay LR at contacts 5 and 9. Before this circuit is 30 broken, a substitute circuit is provided for relay LR at its own contacts 19 and 21 and the contact 20 of relay CO. A circuit is now closed for operating the line switch stepping magnet ST as follows:—ground GA, contact 22 of relay LR, terminal 23 and line switch wiper 24, contact 25 of relay CO, contact 28 and winding 29 of stepping magnet ST to the source of current. The magnet ST energizes its armature, breaks its 35 own circuit at contact 28 and, upon retracting its armature, moves the wipers 4, 10, 14, 17 and 24 one step, i. e., from the first to the second row of terminals. Wiper 14 breaks the original circuit for relay CO but, 40 assuming the trunk to which the second row of terminals leads to be busy, this relay does not release because of the following locking circuit:—ground GB, contact 26 of a relay like CO, wiper 24 and terminal 31 of a line 45 switch like L which is using this trunk, by way of the line switch bank multiple to terminal 31 of this calling line switch L, wiper 24, contact 27 of relay CO, winding 30 of relay CO to the source of current. This 50 busying ground also causes the stepping

magnet ST to operate by way of contact 25 of relay CO and go to the third row of terminals from which point it will be advanced in the same manner as described for the first row.

70

As long as the line switch wipers are away from their "home" points and on a "trunk" point, ground GC is extended by way of wiper 17 to the connector terminal 18, to cause the line to test busy.

75

The cut off relay CO now releases, because there is no ground on either winding, and extends the line conductors 1 and 2 to the connector CN by way of contacts 5 and 9 and line switch wipers 4 and 10. Ground 80 connection GB is now extended through contact 26 of relay CO, wiper 24 and terminal 32 of line switch L, to trunk wire 33 leading to the connector CN, for busying this trunk and thereby causing other line 85 switches like L to pass over this multiple on their banks. The relay CO, upon releasing, breaks the circuit of relay LR at contact 20 which allows LR to release.

85

The closed circuit of the calling line is now extended to the connector CN and causes relays T and R to operate over the following circuit:—ground GD, winding of relay T, connector trunk wire 34, terminal 35 and wiper 4 of line switch L, contact 5 of relay CO, line conductor 2, previously traced closed circuit of substation A, line conductor 1, contact 9 of relay CO, wiper 10 and terminal 36 of line switch L, connector trunk wire 37, winding of relay 100 R to the source of current. Both relays T and R now energize R closing the following circuit:—ground GE, contact 39 of relay R, terminal 40 and wiper 41 of "change-over" switch CHO, contact 42 and winding of "change-over" switch stepping magnet MO to the source of current. Magnet MO now energizes, breaks its own circuit at contact 42, retracts its armature and moves wipers 41, 43 and 44 in a clock-wise 105 direction to the second set of terminals.

105

Assuming the subscriber at substation A to be calling the subscriber at substation B, B's number being 20; as the calling device is pulled forward contact 45 opens and contacts 46 and 47 close, 46 short circuiting the transmitter *t* to eliminate its variable resistance from the line circuit during impulsive and 47 short circuiting the primary induction coil *i* so that the calling subscriber will 110 not hear the objectionable clicks caused by the impulses being sent. As the dial returns, the substation impulse springs 7 are operated twice (the first digit of the desired number being 2) momentarily, each time 115 breaking the circuit of the connector relays T and R, both of them releasing. At the first break, relay R closes the following circuit: ground GE, contact 48 of relay R, terminal 49 and wiper 41 of switch CHO, con- 120

120

125

130

4 tact 42 and winding of magnet MO to the source of current. This causes switch CHO to advance its wipers 41, 43 and 44 to the third row of terminals. This same ground 5 GE by way of contact 48 of relay R also extends to wiper 44 of switch CHO, terminals 50, or 51, connector side switch wiper 52, and first position contact thereof, winding of primary magnet PM to the source of current. The wire to connector side switch 10 52 is multiplied to points 50, 51 and 53 of switch CHO wiper 44 and is for the purpose of delivering the full impulse of relay R to the connector switch operating magnet. To 15 prevent this circuit being interrupted as wiper 44 moves from one point to another, the wiper 44 is made bridging, i. e., it makes connection with the succeeding contact before breaking from the preceding contact.

20 Calling device impulse contact 7 is now closed, whereupon relays T and R energize, T closing the following circuit:—ground GD, contact 54 of relay T, terminal 55 and wiper 41 of switch CHO, contact 42 and winding of stepping magnet MO. This causes wipers 41, 43 and 44 to advance to the 25 fourth set of terminals where the same circuit again operates magnet MO and moves the wipers 41, 43 and 44 to the fifth set of terminals. Here the following circuit is 30 closed:—ground GE, contact 39 of relay R, terminal 60 and wiper 41 of switch CHO, contact 42 and winding of stepping magnet MO to the source of current. This causes the switch CHO to advance to the next set of terminals, which is the first, and from here the same circuit by way of terminal 40 again steps the wipers 41, 43 and 44 to the second set of terminals.

35 40 Calling device contact 7 is now again opened, causing the same series of operations as before, i. e., CHO switch wipers 41, 43 and 44 will advance to the third row of terminals and another impulse will be delivered to the connector primary magnet PM; as previously described for the first break of contact 7 at substation A. Immediately after this second opening of contact 45 7, contacts 46 and 47 are opened and contact 45 is closed. This places relay C, of the substation apparatus, in the line circuit for a sufficient time, before the closure of contact 7, for relay C to operate. Relay C, in operating, breaks its contact 6 which 50 opens the path for the short circuit around its winding placed there by the closure of contact 7. Relay C is of sufficiently high resistance to prevent the operation of marginal relay R at the connector CN, but will 55 permit sensitive relay T to operate. Relay T operates and, as before, closes a circuit from ground GD, contact 54 of relay T, terminal 55 and wiper 41 of switch CHO, contact 42 and winding of magnet MO. This 60 causes CHO switch wipers 41, 43 and 44 to advance to the fourth position and here the same circuit by way of terminal 56 causes these wipers to be advanced to the fifth position. At this point, because relay R is de-energized, a circuit is closed from 65 ground GE, contact 48 of relay R, wiper 44 and terminal 61 of switch CHO, winding 62 of escape magnet ESC, resistance coil RS to the source of current. This causes the escape magnet ESC to energize and lock 70 through its contact 63 to the ground GD by way of contact 54 of relay T. The following circuit is now closed: ground GF, off normal contact 66, contact 67 of busy relay BY, connector side switch wiper 65 and first 75 position thereof, contact 64 of the escape magnet ESC, winding of relay R to the source of current. This causes three things to happen, first, relay R energizes, second, because of the short circuit placed on the calling line by this above traced circuit, the relay C at substation A releases and short circuits itself, third, relay T de-energizes and opens the locking circuit of the escape magnet ESC, which releases and takes the short circuit off the line, allowing relay R 80 to again energize. Relay C does not energize at this time because it will be short circuited by the impulse contact 7 and its own contact 6, the last closure of impulse contact 7 having taken place before these other functions, which have been described, had time to occur. Relay R, upon energizing, causes wipers 41, 43 and 44 of switch CHO to advance to the second set of terminals over the circuit previously traced. Magnet ESC, upon de-energizing, allows the connector side switch wipers 52, 65, 68, 69 and 70 to advance to the second position.

85 90 95 100 105 110 115 120 125 130 From the foregoing it will be seen that, when the calling subscriber dials the first digit, 2, the following is the sequence of operations which the different parts perform:—First—connector seized, “change-over” switch moved one step. Second—opening of calling device impulse springs, connector wipers stepped to first level and “change-over” switch moved one step. Third—closure of calling device impulse springs, “change-over” switch moved four steps, coming to rest on the second point. Fourth—opening of calling device impulse springs, connector wipers stepped to second level and “change-over” switch moved one step. Fifth—closure of calling device circuit through high resistance coil “C,” “change-over” switch moved two steps, coming to rest on the fifth point. Sixth—escape magnet operates, restores the telephone and switch circuits to the starting point for the second digit, i. e., “change-over” switch to its second point, side switch wipers in second position and the 2000 ohms resistance at telephone short-circuited. Thus it will be seen that the “change-over” switch

- CHO makes one complete cycle, coming to rest on the second set of terminals, for each impulse (opening and closure) sent in from the calling device and after the last impulse 5 of the series has been sent, this "change-over" switch stops at the fifth set of terminals and causes the connector circuit to be switched from the primary to the secondary operating magnet.
- 10 The calling subscriber now operates his dial for the second digit, O, of the called number, causing the apparatus to function as before except that this time ten, instead of 2, impulses will be delivered to secondary 75 magnet SM because number O is pulled on the dial and because side switch wiper 52 is in second position. This circuit to magnet SM goes through contact 71 of relay BY so that, if the dial is again turned without releasing on a call to a busy line, the connector switch wipers will not be advanced, and a wrong connection made.
- 15 When the second "change-over" is made, in the same way as the first, the "change-over" switch wipers 41, 43 and 44 are left on the second point and the side switch wipers 52, 65, 68, 69 and 70 are moved to the third position when the following circuit is closed:—ground GG, side switch 20 wiper 68 and third position thereof, connector wiper 57, called line terminal 72, sleeve trunk 73 to called line switch M, line switch wiper 74, terminal 75, winding 76 of cut off relay OC to the source of current. This 25 energizes the called line switch cut off relay OC, opens the line switch battery bridge of the called line at contacts 77 and 78 and closes the following circuit to ring the called party's bell:—common A. C. generator GN, 30 common interrupter INT, common lamp LP, winding of generator cut off relay TR, side switch wiper 70 and third position thereof, connector wiper 59 terminal 80, ring trunk 81 to called line switch M, called line conductor 35 82, ringer r i at substation B, condenser L, impulse contact 83, contact 84 of relay D, line conductor 85, tip trunk 86 of called line switch, connector terminal 87, connector wiper 58, side switch wiper 69 40 and third position thereof, ground GH, through the battery and common resistance coil SR to the other side of the common generator GN. When the side switch wipers went to third position the following circuit 45 was closed to energize the escape magnet ESC:—ground GF, off normal contact 66, contact 67 of relay BY, side switch wiper 65 and third position thereof, winding 62 of magnet ESC, resistance coil RS to the source 50 of current.
- 55 When the called subscriber answers, a direct current path is closed at switch hook contact 79 in the above traced circuit which causes relay TR to operate and close the following circuit:—ground GJ, contact 88 60 of relay TR, through resistance coil RS to battery. This short circuits the escape magnet winding 62, allowing it to release and advance the side switch wipers, 52, 65, 68, 69 and 70 to the fourth position. Here the 70 talking current for the called party, fed through impedance coil AB, is substituted for the ringing current above described, by side switch wipers 69 and 70 moving from the third to the fourth positions. The talking battery for the calling substation transmitter is fed through relays T and R and the path for the voice currents is through condensers 105 and 106.
- 75 After the conversation is completed the 80 connection is released, by the hanging up of the receiver r at the calling substation A, in the following manner:—by opening the circuit at hook switch contact 8, relays T and R at connector switch CN de-energize. Relay R, by closing its contact 48, causes the "change-over" switch CHO to move to position three where the following circuit is closed:—ground GD, contact 89 of relay T, terminal 90 and wiper 43 of "change-over" switch CHO, winding of relay RL and contact 91 thereof, common interrupter contact 92, common resistance coil ES to the source of current. It may here be mentioned that interrupters 121 and 122 are common 95 to the exchange and are turned in the direction indicated by the arrows by the same shaft 113. Therefore when the above circuit is closed, the interrupter contact 92 may or may not be closed, if not closed nothing will happen until interrupter 122 gets to the point where it causes the closure of contact 92. When this circuit is completed, relay RL operates, locks by way of its contact 95, and resistance coil SE, opens its 100 energizing circuit at contact 91 and closes its contact 94. Now, after a certain time interrupter 121 closes contact 93, this time being sufficient to make sure that this is the release condition and not an impulse 105 opening. If relay RL was operated during impulsion, it would release before interrupter 121 could close its contact and cause a release of the switch, because it would de-energize when relay T again energized and opened contact 89. When 110 121 interrupter contact 93 is closed, the following circuit is established:—ground GK, interrupter contact 93, contact 94 of relay RL, contact 96 and winding 99 of connector 115 120 release magnet REL to the source of current. This energizes the release magnet REL which locks from ground GL, low winding 100 and contact 102 of magnet REL, resistance coil RE to the source of current. 125 The connector switch wipers and side switch wipers are now restored to normal when contact 103 is opened. A circuit is also traced from ground GL, winding 100 and contact 102 of magnet REL, connector 130

trunk wire 38, terminal 104 and wiper 14 of line switch L, winding 15 of cut off relay CO to the source of current. This circuit energizes the line switch cut off relay CO and keeps the connector release magnet REL locked. A circuit may now be traced from ground GL, winding 100 and contact 101 of magnet REL, connector trunk wire 33, terminal 32 and wiper 24 of line switch L, contact 25 of relay CO, contact 28 and winding 29 of line switch stepping magnet ST to the source of current, which causes the calling line switch L to take a step and go to its "home" point ready for use in again selecting an idle connector. When connector CN restored its wipers to normal, the cut off relay OC of the called line switch M was released. The following circuit is also closed to cause the release of the "change-over" switch CHO:—ground GD, terminals 90, 114 and 115 of switch CHO, wiper 43 of switch CHO, contacts 97 and 98 of connector release magnet REL, contact 42 and winding MO of switch CHO to the source of current. In multiple with this circuit is winding 99 of magnet REL to the source of current. Thus the connector release magnet, upon energizing, will remain locked until the connector shaft reaches normal, until the line switch L is released and until the "change-over" switch CHO is restored to normal, whereupon magnet REL and relay RL are de-energized. Until magnet REL is de-energized, ground GL, low winding 100 and contact 101 of magnet REL, is maintained in connection with multiple terminal 32 of all line switches in the group to keep this trunk busy.

A call to a busy line will now be described. Assuming that the same number, 20, was dialed and that, at the end of the second digit, the escape magnet ESC operates as before, relay R will be energized, relays C and T will be de-energized and switch CHO will rest on point 2. Escape magnet ESC will not release at this time because of the following locking circuit:—ground on terminal 72, (placed there either from side switch wiper 68 and wiper 57 of some connector like CN which has called this same number or, if the subscriber having this number has made a call, a ground will be placed on terminal 72 in the same manner as was previously described for placing a ground on terminal 18 by line switch L) connector wiper 57, side switch 68 and second position thereof, contact 110 of relay BY, winding of relay BY, contact 108 of escape magnet ESC, winding 107 of magnet ESC to the source of current. This circuit also causes relay BY to energize and lock itself in series with magnet ESC, holding them both, from ground GF, off normal contact 66, contact 109 of relay BY, winding of relay BY, contact 108 and winding 107 of

magnet ESC to the source of current. Relay BY opens contact 67 which removes the short circuit from the calling line and allows relay T to energize. Relay BY also closes contact 111 which extends the common busy tone wire 112, leading from busy tone induction coil BZ, through condenser 105, connector trunk wire 34, line switch terminal 35 and wiper 4, contact 5 of cut off relay CO, calling line conductor 2, through the substation apparatus A, line conductor 1, contact 9 of relay CO, line switch wiper 10 and contact 36, connector trunk wire 37, winding of relay R, through the battery to ground GE and then to the other side of busy induction coil BZ. This gives the calling subscriber a tone which indicates that the called for line is busy and when he hangs up his receiver, the connection is released in the same manner as previously described.

From the above narrative it is apparent that I have evolved a system wherein neither primary impulse relays T and R need to be relatively slow operating, or may both operate at the same speed or at slightly different speeds, and in connection with such relays I have evolved a system wherein the "change-over" function is performed positively, and wherein the release of the switch is accomplished in a positive way without dependence being placed upon the co-operation of "fast and slow" relays; also that this is accomplished in a system free from any necessary grounds at the substations or third wire connection thereto; a full use of a metallic talking circuit at the same time being had.

I am aware that numerous and extensive departures may be made from the embodiment of my invention illustrated and described but without departing from the spirit thereof. For instance, I am aware that other equivalent means may be provided for many of the elements herein specifically discussed, but what I claim as my invention is defined in the following claims:

1. In a telephone system, the combination with a plurality of substations, a main station, switching mechanism at the main station adapted to make connection with a desired called substation, line conductors connecting the said switching mechanism and a calling substation, a circuit interrupter at the substation and a source of current associated with the said switching mechanism, means to cause the said circuit interrupter to interrupt the circuit of the line conductors a definite predetermined number of times, means operative upon the subsequent closure of the said line conductors by the said interrupter to interpose a high resistance in said circuit, a pair of relays for controlling the said switching mechanism under the control of the said circuit interrupter,

each of the said relays being responsive to circuit closures with normal current flowing over the line conductors, and only one of the said relays being responsive to the closure of 5 the said line conductors through the said resistance.

2. In a telephone system, the combination with a plurality of substations, a main station, switching mechanism at the main station 10 adapted to make connection with a desired called substation, line conductors connecting the said switching mechanism and a calling substation, a circuit interrupter at the substation and a source of current associated with the said switching mechanism, means to cause the said circuit interrupter to interrupt the circuit of the line conductors a definite predetermined number of times, means operative upon a subsequent closure 15 of the said line conductors by the said interrupter to interpose a high resistance in said circuit, a pair of relays for controlling the said switching mechanism under the control of the said circuit interrupter, each 20 of the said relays being responsive to circuit closures with normal current flowing over the line conductors, and only one of the said relays being responsive to the closure of the said line conductors through the said resistance, and "change-over" switching 25 means adapted to be operated under the joint control of the said pair of relays when one of the said pair is operated and the other relay is quiescent. 30

3. In a telephone system, the combination with a plurality of substations, a main station, switching mechanism at the main station adapted to make connection with a desired called substation, line conductors connecting the said switching mechanism and a calling substation, a circuit interrupter at the substation and a source of current associated 35 with the said switching mechanism, means to cause the said circuit interrupter to interpose a high resistance in said circuit, a pair of relays for controlling the said switching mechanism under the control of the said circuit interrupter, each of the said relays being responsive to circuit closures 40 with normal current flowing over the line conductors, and only one of the said relays being responsive to the closure of the said line conductors through the said resistance, "change-over" switching means adapted to 45 be operated under the joint control of the said pair of relays when one of the said pair is operated and the other relay is quiescent, locking means for the said resistance interposing means at the substation, and unlocking means for the said locking means under 50 the control of the said "change-over" switching means. 55

4. In a telephone system, the combination with a plurality of substations, a main station, switching mechanism at the main station adapted to make connection with a desired called substation, line conductors connecting the said switching mechanism and a calling substation, a circuit interrupter at 60 the substation and a source of current associated with the said switching mechanism, means to cause the said circuit interrupter to interrupt the circuit of the line conductors a definite predetermined number of times, 65

4. In an automatic telephone system, the combination with telephone lines, substations for the lines, a main station wherein the lines terminate, switching mechanism at the main station, means to interlink a calling 70 line with the said switching mechanism, a pair of relays controlling the said switching mechanism under the control of calling substation apparatus, a circuit interrupter at the substation, means to variably operate the 75 said circuit interrupter to interrupt the circuit of the calling line a predetermined number of times, means to include a resistance in circuit with the said line after the end of each series of circuit interruptions, a 80 source of current, and circuit connections to cause the operation of each of the said relays at each normal closure of the line circuit, one of the said relays being irresponsible to the said closure through the said 85 resistance.

5. In a telephone system, the combination with a plurality of substations, a main station, switching mechanism at the main station adapted to make connection with a desired called substation, line conductors connecting the said switching mechanism and a calling substation, a circuit interrupter at the substation and a source of current associated 90 with the said switching mechanism, means to cause the said circuit interrupter to interrupt the circuit of the line conductors a definite predetermined number of times, means operative upon a subsequent closure of the said line conductors by the said interrupter 95 to interpose a high resistance in said circuit, a pair of relays for controlling the said switching mechanism under the control of the said circuit interrupter, each of the said relays being responsive to circuit closures 100 with normal current flowing over the line conductors, and only one of the said relays being responsive to the closure of the said line conductors through the said resistance, "change-over" switching means adapted to 105 be operated under the joint control of the said pair of relays when one of the said pair is operated and the other relay is quiescent, locking means for the said resistance interposing means at the substation, and unlocking means for the said locking means under 110 the control of the said "change-over" switching means. 115

6. In a telephone system, the combination with a plurality of substations, a main station, switching mechanism at the main station adapted to make connection with a desired called substation, line conductors connecting the said switching mechanism and a calling substation, a circuit interrupter at 120 the substation and a source of current associated with the said switching mechanism, means to cause the said circuit interrupter to interrupt the circuit of the line conductors a definite predetermined number of 125 times, means to prevent the operation of the said "change-over" switching means when both of the said relays are operated. 130

times, means operative upon a subsequent closure of the said line conductors by the said interrupter to interpose a high resistance in said circuit, a pair of relays for controlling the said switching mechanism under the control of the said circuit interrupter, each of the said relays being responsive to circuit closures with normal current flowing over the line conductors, and only one of the said relays being responsive to the closure of the said line conductors through the said resistance, "change-over" switching means adapted to be operated under the joint control of the said pair of relays when one of the said pair is operated and the other relay is quiescent, means to prevent the operation of the said "change-over" switching means when both of the said relays are operated, locking means for the said resistance interposing means at the substation, and unlocking means for the said locking means under the control of the said "change-over" switching means.

7. In an automatic telephone system, the combination with telephone lines, substations for the lines, a main station wherein the lines terminate, switching mechanism at the main station, means to interlink a calling line with the said switching mechanism, a pair of relays controlling the said switching mechanism under the control of calling substation apparatus, a circuit interrupter at the substation, means to variably operate the said circuit interrupter to interrupt the circuit of the calling line a predetermined number of times, means to include a resistance in circuit with the said line after the end of each series of circuit interruptions, a source of current, circuit connections to cause the operation of each of the said relays at each normal closure of the line circuit, one of the said relays being irresponsible to the said closure through the said resistance, and "change-over" switching means adapted to be operated under the joint control of the said pair of relays, when one of the said pair is operated and the other is quiescent.

8. In an automatic telephone system, the combination with telephone lines, substations for the lines, a main station wherein the lines terminate, switching mechanism at the main station, means to interlink a calling line with the said switching mechanism, a pair of relays controlling the said switching mechanism under the control of calling substation apparatus, a circuit interrupter at the substation, means to variably operate the said circuit interrupter to interrupt the circuit of the calling line a predetermined number of times, means to include a resistance in circuit with the said line after the end of each series of circuit interruptions, a source of current, circuit connections to cause the operation of each of the said relays at each

normal closure of the line circuit, one of the said relays being irresponsible to the said closure through the said resistance, "change-over" switching means adapted to be operated under the joint control of the said pair of relays, when one of the said pair is operated and the other is quiescent, and means to prevent the operation of the said "change-over" switching means while both of the said relays are operated. 75

9. In an automatic telephone system, the combination with telephone lines, substations for the lines, a main station wherein the lines terminate, switching mechanism at the main station, means to interlink a calling line with the said switching mechanism, a pair of relays controlling the said switching mechanism under the control of calling substation apparatus, a circuit interrupter at the substation, means to variably operate the said circuit interrupter to interrupt the circuit of the calling line a predetermined number of times, means to include a resistance in circuit with the said line after the end of each series of circuit interruptions, a source of current, circuit connections to cause the operation of each of the said relays at each normal closure of the line circuit, one of the said relays being irresponsible to the said closure through the said resistance, "change-over" switching means adapted to be operated under the joint control of the said pair of relays when one of the said pair is operated and the other is quiescent, locking means for the said resistance interposing means at the substation, and unlocking means for the said locking means under the control of the said "change-over" switching means. 80 85 90 95

10. In an automatic telephone system, the combination with telephone lines, substations for the lines, a main station wherein the lines terminate, switching mechanism at the main station, means to interlink a calling line with the said switching mechanism, a pair of relays controlling the said switching mechanism, under the control of calling substation apparatus, a circuit interrupter at the substation, means to variably operate the said circuit interrupter to interrupt the circuit of the calling line a predetermined number of times, means to include a resistance in circuit with the said line after the end of each series of circuit interruptions, a source of current, circuit connections to cause the operation of each of the said relays at each normal closure of the line circuit, one of the said relays being irresponsible to the said closure through the said resistance, "change-over" switching means adapted to be operated under the joint control of the said pair of relays, when one of the said pair is operated and the other is quiescent, means to prevent the operation of the said "change-over" switching means 110 115 120 125 130

while both of the said relays are operated, locking means for the said resistance interposing means at the substation, and unlocking means for the said locking means under the control of the said "change-over" switching means.

11. In an automatic telephone system, the combination with telephone lines, substations for the lines, a main station wherein the lines terminate, switching mechanism at the main station, means to interlink a calling line with the said switching mechanism, a pair of relays directly controlling the said switching mechanism under the control of calling substation apparatus, including a substation circuit interrupter, means to variably operate the said circuit interrupter to produce successive series of calling line circuit interruptions, means including an electromagnet to include a resistance in series with the said line immediately following each series of circuit interruptions, a source of current, and circuit connections to cause the operation of each of the said relays at each normal closure of the line circuit, one of the said relays being irresponsible to the final closure after the last circuit interruption of each series through the said resistance.

12. In an automatic telephone system, the combination with telephone lines, substations for the lines, a main station wherein the lines terminate, switching mechanism at the main station, means to interlink a calling line with the said switching mechanism, a pair of relays directly controlling the said switching mechanism under the control of calling substation apparatus, including a substation circuit interrupter, means to variably operate the said circuit interrupter to produce successive series of calling line circuit interruptions, means including an electromagnet to include a resistance in series with the said line immediately following each series of circuit interruptions, a source of current, circuit connections to cause the operation of each of the said relays at each normal closure of the line circuit, one of the said relays being irresponsible to the final closure after the last circuit interruption of each series through the said resistance, and "change-over" switching controlling means adapted to be operated under the joint control of the said pair of relays when one of the said pair is operated and the other relay is quiescent.

13. In an automatic telephone system, the combination with telephone lines, substations for the lines, a main station wherein the lines terminate, switching mechanism at the main station, means to interlink a calling line with the said switching mechanism, a pair of relays directly controlling the said switching mechanism under the control of calling substation apparatus, including a substation circuit interrupter,

means to variably operate the said circuit interrupter to produce successive series of calling line circuit interruptions, means including an electromagnet to include a resistance in series with the said line immediately following each series of circuit interruptions, a source of current, circuit connections to cause the operation of each of the said relays at each normal closure of the line circuit, one of the said relays being irresponsible to the final closure after the last circuit interruption of each series through the said resistance, "change-over" switching controlling means adapted to be operated under the joint control of the said pair of relays when one of the said pair is operated and the other relay is quiescent, a locking circuit for the said electromagnetic resistance including means, means to maintain the said locking circuit operative under the control of the said electromagnet after an initial operation thereof, and circuit unlocking means responsive to the complete operation of the said "change-over" means to unlock the said circuit to disable the said resistance including means.

14. In an automatic telephone system, the combination with telephone lines, substations for the lines, a main station wherein the lines terminate, switching mechanism at the main station, means to interlink a calling line with the said switching mechanism, a pair of relays directly controlling the said switching mechanism under the control of calling substation apparatus, including a substation circuit interrupter, means to variably operate the said circuit interrupter to produce successive series of calling line circuit interruptions, means including an electromagnet to include a resistance in series with the said line immediately following each series of circuit interruptions, a source of current, circuit connections to cause the operation of each of the said relays at each normal closure of the line circuit, one of the said relays being irresponsible to the final closure after the last circuit interruption of each series through the said resistance, "change-over" switching controlling means adapted to be operated under the joint control of the said pair of relays when one of the said pair is operated and the other relay is quiescent, and means to prevent the operation of the said "change-over" switching means during the period wherein at any time both of the said relays are operated.

15. In an automatic telephone system, the combination with telephone lines, substations for the lines, a main station wherein the lines terminate, switching mechanism at the main station, means to interlink a calling line with the said switching mechanism, a pair of relays directly controlling the said switching mechanism under the control of calling substation apparatus, including a

substation circuit interrupter, means to variably operate the said circuit interrupter to produce successive series of calling line circuit interruptions, means including an electromagnet to include a resistance in series with the said line immediate following each series of circuit interruptions, a source of current, circuit connections to cause the operation of each of the said relays at each 10 normal closure of the line circuit, one of the said relays being irresponsible to the final closure after the last circuit interruption of each series through the said resistance, "change-over" switching controlling means 15 adapted to be operated under the joint control of the said pair of relays when one of the said pair is operated and the other relay is quiescent, means to prevent the operation of the said "change-over" switching means 20 during the period wherein at any time both of the said relays are operated, a locking circuit for the said electromagnetic resistance including means, means to maintain the said locking circuit operative under the control 25 of the said electromagnet after an initial operation thereof, and circuit unlocking means responsive to the complete operation of the said "change-over" means to unlock the said circuit to disable the said resistance including means.

16. In an automatic telephone system, the combination with telephone lines, substations for the lines, a main station wherein the lines terminate, an automatic numerical switch at the main station, a non-numerical switch to interlink a calling line with the said numerical switch, a pair of relays for the said numerical switch, means at the substation to produce successive series of circuit 30 interruptions, means at the substation to operate both of the said pair of relays substantially in unison during each circuit interruption of a series, substation controlling means for differently operating the relays for a period immediately following the last circuit interruption of a series, a plurality 35 of operating magnets for the said numerical switch, one of which is operative under said substation control to move the switch in a primary direction during a first series of circuit interruptions, a second of which is operative to be moved in a secondary direction during a second series of circuit interruptions, "change-over" means to remove the primary operating magnet from the control of the said pair of relays and to place the secondary operating magnet under the control of the said pair of relays, and means to cause the operation of the said "change-over" means 40 45 50 55 60 65 70 75 80 85 90 95 100 105 110 115 120 125 130

lines terminate, an automatic numerical switch at the main station, a non-numerical switch to interlink a calling line with the said numerical switch, a pair of relays for the said numerical switch, means at the substation to produce successive series of circuit interruptions, means at the substation to operate both of the said pair of relays substantially in unison during each circuit interruption of a series, substation controlling means for differently and continuously operating the relays for a period immediately following the last circuit interruption of a series, a plurality of operating magnets for the said numerical switch, one of which is operative under substation control to move the switch in a primary direction during the first series of circuit interruptions, a second of which is operative to move the switch in a secondary direction during a second series of circuit interruptions, "change-over" means to remove the primary operating magnet from the control of the said pair of relays and to place the secondary operating magnet under the control of the said pair of relays, 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

17. In an automatic telephone system, the combination with telephone lines, substations for the lines, a main station wherein the

100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

from the control of the said substation controlling means, and separate controlling means for the said numerical switch to prevent improper operation of the said "change-over" means due to differing response rates for the said relays to circuit interruptions.

19. In an automatic telephone system, the combination with telephone lines, substations for the lines, a main station wherein the lines terminate, an automatic numerical switch at the main station, circuit connections interlinking a calling line with the said numerical switch, a pair of relays for the said numerical switch, means at the substation to produce successive series of circuit interruptions, means at the substation to operate both of the said pair of relays substantially in unison during each circuit interruption of a series, substation controlling means for differently and continuously operating the relays for a period immediately following the last circuit interruption of a series, a plurality of operating magnets for the said numerical switch, one of which is operative under substation control to move the switch in a primary direction during the first series of circuit interruptions, a second of which is operative to move the switch in a secondary direction during the second series of circuit interruptions, "change-over" means to remove the primary operating magnet from the control of the said pair of relays and to place the secondary operating magnet under the control of the said pair of relays, means at the substation controlling means for differently and continuously operating the relays for a period immediately following the last circuit interruption of a series, a plurality of operating magnets for the said numerical switch, one of which is operative under substation control to move the switch in a primary direction during the first series of circuit interruptions, a second of which is operative to move the switch in a secondary direction during the second series of circuit interruptions, "change-over" means to remove the primary operating magnet from the control of the said pair of relays and to place the secondary operating magnet under the control of the said pair of relays, means at the substation controlling means, and correcting means under the joint control of the said pair of relays to prevent the improper operation of the said "change-over" means of the said numerical switch, due to the said relays operating at different rates of speed.

20. In an automatic telephone system, the combination with telephone lines, substations for the lines, a main station wherein the lines terminate, an automatic numerical switch at the main station, circuit connections interlinking a calling line with the said numerical switch, a pair of relays for the said numerical switch, means at the substation to produce successive series of circuit interruptions, means at the substation to operate both of the said pair of relays substantially in unison during each circuit interruption of a series, substation controlling means for differently and continuously operating the relays for a period immediately following the last circuit interruption of a series, a plurality of operating magnets for the said numerical switch, one of which is operative under substation control to move the switch in a primary direction during

the first series of circuit interruptions, a second of which is operative to move the switch in a secondary direction during a second series of circuit interruptions, "change-over" means to remove the primary operating magnet from the control of the said pair of relays and to place the secondary operating magnet under the control of the said pair of relays, means to cause the operation of the said "change-over" means responsive to the condition of the differently operated pair of relays resulting from the control of the said substation controlling means, a step-by-step switch for the said numerical switch operating under the control of one of the said relays in response to the said circuit interruptions and circuit connections jointly controlled by the said pair of relays, and contacts of the said step-by-step switch to prevent improper operation of the said "change-over" means on account of the slight differences in the speeds of action or release between the said relays in response to the said circuit interruptions.

21. In a telephone system, the combination with a plurality of telephone lines, substations for the lines, a main station, a selective switch at the main station adapted to interconnect two of the said telephone lines, a source of current, a relay in the circuit of the said source of current leading to a substation of a connected line, a release magnet, a release relay, a timing mechanism, a pair of circuits successively controlled thereby, there being a predetermined interval between the control exercised by the said timing mechanism on the one circuit and the control exercised by the said timing mechanism upon the second circuit, circuit connections to include in the said first circuit a winding of the said release relay, a source of current, contacts of the said substation circuit relay and controlling contacts of the said timing mechanism, circuit connections for the second circuit comprising a winding of the said release magnet, contacts of the said release relay, and controlling contacts of the said timing mechanism.

22. In an automatic telephone system, an automatic selective switch for interconnecting telephone line substations, a telephone line substation controlled relay, a release magnet for the said switch, a release relay, a pair of continuously successively operating controlling sets of contacts, a circuit for the said release relay comprising a first operated set of controlling contacts and contacts of said substation controlled relay, and a circuit for said release magnet comprising a second operated set of controlling contacts and contacts of the said release relay.

23. In an automatic telephone system, the combination with an automatic selective switch for interconnecting telephone line

substations, a telephone line substation controlled relay, a release magnet for the said switch, a release relay, a pair of continuously successively operating controlling sets of 5 contacts, a circuit for the said release relay comprising a first operated set of controlling contacts and contacts of said substation controlled relay, a circuit for said release magnet comprising said second operated set of 10 controlling contacts and contacts of the said release relay, and a locking circuit for the said release relay under the control of off normal contacts of the said switch.

24. In an automatic telephone system, an 15 automatic selective switch for interconnecting telephone line substations, a telephone line substation controlled relay, a release magnet for the said switch, a release relay, a pair of continuously successively operating 20 controlling sets of contacts, a circuit for the said release relay comprising a first operated set of controlling contacts and contacts of said substation controlled relay, a circuit for said release magnet comprising said second operated set of controlling contacts and contacts of the said release relay, and other automatic selective switches for interconnecting other pairs of telephone lines, said pair of sets of controlling contacts being 25 common to all of the said automatic selective switches.

25. In an automatic telephone system, the combination with an automatic selective switch for interconnecting telephone line 30 substations, a telephone line substation controlled relay, a release magnet for the said switch, a release relay, a pair of continuously successively operating controlling sets of contacts, a circuit for the said release 35 relay comprising a first operated set of controlling contacts and contacts of said substation controlled relay, a circuit for said release magnet comprising said second operated set of controlling contacts and contacts of the said release relay, a locking circuit for the said release relay under the control of off normal contacts of the said switch and other automatic selective switches for 40 interconnecting other pairs of telephone lines, said pair of sets of controlling contacts being common to all of the said automatic selective switches.

26. In a telephone system, telephone lines, 45 substations on the lines, automatic switching mechanism for interconnecting a pair of the telephone lines, a calling substation controlled relay, means to release the said relay when the calling substation is retired, two sets of controlling contacts adapted to 50 be successively operated with a definite time interval between the operation of the first set and the operation of the second set, a winding of a release relay, the first set of contacts and normal contacts of the said calling 55 substation controlled relay in a first cir-

cuit, said second set of contacts, normally open contacts of said release relay and a winding of a release magnet in a second circuit, said first circuit controlling the said second circuit to operate the said release 70 magnet, and means including off normal contacts of the said switching mechanism under the control of the said release magnet for controlling the said release relay.

27. In a telephone system, telephone lines, 75 substations for the lines, automatic switching mechanism for interconnecting a pair of the telephone lines, a calling substation controlled relay, means to release the said relay when the calling substation is retired, 80 two sets of controlling contacts adapted to be successively operated with a definite time interval between the operation of the first set and the operation of the second set, a winding of a release relay, the first set of 85 contacts and normal contacts of the said calling substation controlled relay in a first circuit, said second set of contacts normally open contacts of said relay and a winding of a release magnet in a second circuit, said first circuit controlling the said second circuit to operate the said release magnet, means including off normal contacts of the said switching mechanism under the control of the said release relay for 90 controlling the said release magnet, and other switching mechanisms each having a substation controlled relay, release relays and release magnets individual to each, but said time controlling contacts being common to all.

28. In a subscriber operated telephone system, the combination with telephone lines, substations for the subscribers on each of the lines, a plurality of switches at a main 105 station, each adapted to interconnect two of the said lines, a substation controlled relay for each switch under the control of substation apparatus of a calling line, normally closed and normally open contacts for 110 the said relay, a source of current, a release relay, off normal contacts of the said switch a pair of controlling contacts in the circuit of the normal contacts of the said relay, a second pair of controlling contacts, controlling contact operating means adapted to 115 continuously and successively operate the said first named pair of controlling contacts and the second named pair of controlling contacts, a locking circuit for the said release 120 relay adapted to operatively lock the said release relay whenever the said release relay is operated by the closure of the said first-named pair of controlling contacts, said locking circuit also being under the control 125 of normal contacts of the substation controlled relay, a release magnet for the said switch, a winding therefor and a circuit for the said winding including a source of current, normally open contacts of the said 130

release relay and the second operated pair of controlling contacts to operate the said release relay.

29. In a subscriber operated telephone system, the combination with telephone lines, substations for the subscribers on each of the lines, a plurality of switches at a main station, each adapted to interconnect two of the said lines, a substation controlled relay for each switch under the control of substation apparatus of a calling line, normally closed and normally open contacts for the said relay, a source of current, a release relay, off normal contacts of the said switch, a pair of controlling contacts in the circuit of the normal contacts of the said relay, a second pair of controlling contacts, controlling contact operating means adapted to continuously and successively operate the said first named pair of controlling contacts and the second named pair of controlling contacts, a locking circuit for the said release relay adapted to operatively lock the said release relay whenever the said release relay is operated by the closure of the said first-named pair of controlling contacts, said locking circuit also being under the control of normal contacts of the substation controlled relay, a release magnet for the said switch, a winding therefor and a circuit for the said winding including a source of current, normally open contacts of the said release relay and the said second operated pair of controlling contacts to operate the said release magnet, and a locking circuit for the said release magnet including off normal contacts of the said switch.
30. In a subscriber operated telephone system, the combination with telephone lines, substations for the subscribers on each of the lines, a plurality of switches at a main station, each adapted to interconnect two of the said lines, a substation controlled relay for each switch under the control of substation apparatus of a calling line, normally closed and normally open contacts for the said relay, a source of current, a release relay, off normal contacts of the said switch, a pair of controlling contacts in the circuit of the normal contacts of the said relay, a second pair of controlling contacts, controlling contact operating means adapted to continuously and successively operate the said first-named pair of controlling contacts and the second-named pair of controlling contacts, a locking circuit for the said release relay adapted to operatively lock the said release relay whenever the said release relay is operated by the closure of the said first-named pair of controlling contacts, said locking circuit also being under the control of normal contacts of the substation controlled relay, a release magnet for the said switch, a winding therefor and a circuit for the said winding including a source of current, normally open contacts of the said release relay and the second operated pair of controlling contacts to operate the said release magnet, said controlling contact operating means being common to a plurality of the said switches.

31. In a subscriber operated telephone system, the combination with telephone lines, substations for the subscribers on each of the lines, a plurality of switches at a main station, each adapted to interconnect two of the said lines, a substation controlled relay for each switch under the control of substation apparatus of a calling line, normally closed and normally open contacts for the said relay, a source of current, a release relay, off normal contacts of the said switch, a pair of controlling contacts in the circuit of the normal contacts of the said relay, a second pair of controlling contacts, controlling contact operating means adapted to continuously and successively operate the said first named pair of controlling contacts and the second-named pair of controlling contacts, a locking circuit for the said release relay adapted to operatively lock the said release relay whenever the said release relay is operated by the closure of the said first-named pair of controlling contacts, said locking circuit also being under the control of normal contacts of the substation controlled relay, a release magnet for the said switch, a winding therefor and a circuit for the said winding including a source of current, normally open contacts of the said release relay and the second operated pair of controlling contacts to operate the said release magnet, said controlling contact operating means being common to a plurality of the said switches.

32. In a subscriber operated telephone system, the combination with telephone lines, substations for the subscribers on each of the lines, a plurality of switches at a main station, each adapted to interconnect two of the said lines, a substation controlled relay for each switch under the control of substation apparatus of a calling line, normally closed and normally open contacts for the said relay, a source of current, a release relay off normal contacts of the said switch, a pair of controlling contacts in the circuit of the normal contacts of the said relay, a second pair of controlling contacts, controlling contact operating means adapted to continuously and successively operate the said first-named pair of controlling contacts and the second-named pair of controlling contacts, a locking circuit for the said release relay adapted to operatively lock the said release relay whenever the said release relay is operated by the closure of the said first-named pair of controlling contacts, said locking circuit also being under the control of normal contacts of the substation controlled relay, a release magnet for the said switch, a winding therefor and a circuit for the said winding including a source of current, normally open contacts of the said release relay and the second operated pair of controlling contacts to operate the said release magnet, said controlling contact operating means being common to a plurality of the said switches.

said locking circuit also being under the control of normal contacts of the substation controlled relay, a release magnet for the said switch, a winding therefor and a circuit for the said winding including a source of current, normally open contacts of the said release relay and the said second operated pair of controlling contacts to operate the said release magnet, a locking circuit for the said release magnet including off normal contacts of the said switch, both of the said pairs of controlling contacts being common to a plurality of the said switches.

15 33. In a subscriber operated telephone system, the combination with telephone lines, substations for the subscribers of each of the lines, a plurality of switches at a main station, each adapted to interconnect 20 two of the said lines, a substation controlled relay for each switch under the control of substation apparatus of a calling line, normally closed and normally open contacts for the said relay, a source of current, a 25 release relay, off normal contacts of the said switch, a pair of controlling contacts in the circuit of the normal contacts of the said relay, a second pair of controlling contacts, controlling contact operating means 30 adapted to continuously and successively operate the said first-named pair of controlling contacts and the second named pair of controlling contacts, a locking circuit for the said release relay adapted to operatively 35 lock the said release relay whenever the said release relay is operated by the closure of the said first-named pair of controlling contacts, said locking circuit also being under the control of normal contacts of the 40 substation controlled relay, a release magnet for the said switch, a winding therefor and a circuit for the said winding including a source of current, normally open contacts of the said release relay and the said second 45 operated pair of controlling contacts to operate the said release magnet, a locking circuit for the said release magnet including off normal contacts of the said switch, both 50 of the said pairs of controlling contacts being under the control of common control contact actuating means for a plurality of said switches.

34. In a telephone system, incoming circuits, a plurality of outgoing circuits, means 55 including directly controlled automatic switches for interconnecting said incoming circuits with any of said outgoing circuits, a controlling circuit for each switch including two sides of an incoming circuit in series, 60 each switch being advanced in response to momentary interruptions of its controlling circuit and arranged to be released in response to a long interruption of its controlling circuit, and a mechanical device common to a plurality of said switches for pre-

venting the release of any of said automatic switches during momentary interruptions of its controlling circuit.

35. In a telephone system, an incoming line, a plurality of outgoing lines, an automatic switch for interconnecting said incoming line with any of said outgoing lines, a controlling circuit for said switch including two sides of said incoming line in series, said switch being advanced in response to momentary interruptions of said controlling circuit and arranged to be released in response to a long interruption of its controlling circuit, and a constantly operating device for preventing the release of said automatic switch during momentary interruptions of its controlling circuit.

36. In a telephone system, an incoming line, a plurality of outgoing lines, an automatic switch for interconnecting said incoming line with any of said outgoing lines, a controlling circuit for said switch including two sides of said incoming line in series, said switch being advanced in response to momentary interruptions of said controlling circuit and arranged to be released in response to a long interruption of its controlling circuit, and a constantly rotating device for preventing the release of said automatic switch during momentary interruptions of its controlling circuit.

37. In a telephone system, an incoming line, a plurality of outgoing lines, an automatic switch for interconnecting said incoming line with any of said outgoing lines, a controlling circuit for said switch including two sides of said incoming line in series, said switch being advanced in response to momentary interruptions of said controlling circuit and arranged to be released in response to a long interruption of its controlling circuit, and a uni-directional rotary circuit closing switch for preventing the release of said automatic switch during momentary interruptions of its controlling circuit.

38. In a telephone system, an incoming line, a plurality of outgoing lines, an automatic switch for interconnecting said incoming line with any of said outgoing lines, a controlling circuit for said switch including two sides of said incoming line in series, said switch being advanced in response to momentary interruptions of said controlling circuit and arranged to be released in response to a long interruption of its controlling circuit, and a constantly rotating interrupting device for preventing the release of said automatic switch during momentary interruptions of its controlling circuit.

39. In a telephone system, an incoming line, a plurality of outgoing lines, an automatic switch for interconnecting said incoming line with any of said outgoing lines, a

controlling circuit for said switch including two sides of said incoming line in series, said switch being advanced in response to momentary interruptions of said controlling circuit and arranged to be released in response to a long interruption of its controlling circuit, and a constantly rotating timing device for preventing the release of said automatic switch during momentary interruptions of its controlling circuit.

40. In an automatic telephone system, a plurality of telephone lines, means including trunk circuits, non-numerical switches and numerical switches for interconnecting said lines, a line relay normally bridged to each

telephone line circuit, a cut-off relay associated with each telephone line circuit and controlled over a selected trunk circuit to disconnect said line relay from its associated line during conversation and to re-connect 20 said line relay to said telephone line at the close of conversation, releasing means for said non-numerical switch, a timing device common to a plurality of non-numerical switches and means including said timing 25 device and a cut-off relay for operating said releasing means.

In testimony whereof, I hereunto subscribe my name this 22nd day of Jan., A. D. 1919.

WINFRED T. POWELL.
